UNITED STATES PATENT OFFICE.

FRANK E. BROWN, OF SAN FRANCISCO, CALIFORNIA.

SHOE-STITCHING-MACHINE ATTACHMENT.

1,272,910.

Specification of Letters Patent. Patented July 16, 1918.

Application filed July 23, 1917. Serial No. 182,254.

To all whom it may concern:

Be it known that I, FRANK E. BROWN, a citizen of the United States, and resident of San Francisco, in the county of San Francisco and State of California, have invented 5 certain new and useful Improvements in Shoe - Stitching - Machine Attachments, of which the following is a specification.

This invention relates to new and useful 10 improvements in shoe stitching machines, and the primary object of the invention is to provide an attachment adapted to be applied to the needle plate of a conventional and well known type of shoe stitching machine, that acts as a guard to render the channeling attachment on the needle plate 15 inoperative. The channeling attachment on the needle plate of the well known type of shoe stitching machines to which this device is adapted to be applied, is only for use, when the machine is stitching leather soles, as the same channels the soles, and stitches 20 in said channel. Where it is desired to stitch a sole formed of some rubber composition, the channeling operation is useless, and is detrimental to the stitching, as the same is liable to pull through. My attachment comprises a guard means which is 25 adapted to be quickly applied over the needle plate, to cover up the channeling knife, so that the machine is adapted to 30 stitch rubber composition soles, as well as leather soles, with no material change to the structure thereof.

35 Another object of the invention is to provide a device of this character, which is easily and simply constructed, inexpensive to manufacture, and one which will be very efficient in operation.

40 With these and numerous other objects in view, my invention consists of the novel features of construction, combination and arrangement of parts which will be herein referred to and more particularly pointed 45 out in the specification and claims.

In the accompanying drawings:

Figure 1 is a longitudinal section through the guard plate, showing the same in position over a needle plate; and

50 Fig. 2 is a detached perspective view of the needle plate and guard plate.

In describing my invention I shall refer to the drawing in which similar reference characters designate corresponding parts 55 throughout the several views.

The numeral 1 designates a needle plate,

such as is ordinarily used on a certain well known type of shoe stitching machine, said needle plate being provided with the conventional apertures 2 therein, through which 60 fastening means are positioned to secure the plate to the machine. One end edge of the plate is inclined as shown at 3, and adjacent the same is a transversely extending elongated slot 4, the purpose of which is obvious. The plate 1 is provided adjacent one end of the slot 4, with an upstanding channeling knife 5, which channels the shoe sole during the ordinary operation of the machine. 70

The above described parts, namely the needle plate and its construction are of the conventional type used on the certain well known type of machine, and form no part whatsoever of my invention. My invention 75 comprises primarily a guard means, which is adapted to be positioned over the needle plate, so as to render the channeling knife inoperative, whereby the machine is adapted 80 for use in stitching soles of rubber composition.

The guard attachment comprises a plate 6, which is correspondingly shaped to the needle plate 1, being provided at one end edge with an inclined portion 7, and adjacent the same an elongated transversely extending slot 8, that is adapted for alignment with the slot 4 in the needle plate, when the guard plate is in position. The guard plate is provided with downwardly projecting 90 flanges 9 on its edges, said flanges being adapted to engage the base portion on which the needle plate 1 is positioned, adjacent the edges of the same, to hold the guard plate in spaced superposed relation above said 95 needle plate. It is obvious that the guard plate 6 is slightly larger than the needle plate, so that the downwardly bent flanges, will be disposed beyond the edges of said 100 needle plate. The flanges will snugly engage the edges of the needle plate, so as to insure a positive engagement between these parts.

In operation, when it is desired to obviate the use of the channeling attachment or 105 knife 5, so that the machine will stitch a rubber composition sole, without channeling the same, the guard plate 6 is positioned over the needle plate 1, the downwardly projecting flanges 9 thereon snugly engaging 110 the side edges of the needle plate, so that the top portion of the guard plate will be

disposed in spaced superposed relation above said needle plate. The slot 8 in the guard plate will align with the slot 4 in the needle plate, so as the machine will be adapted to 5 operate in the conventional manner. When the guard plate is in position, it is obvious that the channeling knife 5 will be covered, and a sole may be moved along the guard plate and stitched, without said sole being 10 channeled. No additional securing means are necessary to hold the guard plate in position, as the pressure of the sole on the same, and the snug engagement between the plates will be sufficient to accomplish this 15 purpose, and hold the plate in operative relation.

This attachment to a shoe stitching machine will be found especially useful in shoe repairing shops, that specialize on quick 20 work, that is repairing the shoes while the customer waits. Heretofore to prevent channeling a rubber composition sole, it was necessary to entirely remove the needle plate, but by the use of this attachment, it may be 25 quickly covered, so as to prevent the composition sole from being channeled, thereby creating a great saving in time and labor. The attachment may be very economically manufactured, as the same is formed from 30 a single piece of metal, of plainly simple construction. The attachment is applied without the necessity of additional fastening means, it only being necessary to place the guard plate over the needle plate, whereby 35 the pressure of the shoe thereon while being stitched, and the snug engagement between the downwardly extending flanges, and the needle plate will insure the attachment against accidental displacement.

Copies of this patent may be obtained for five cents each, by addressing the "Commissioner of Patents, Washington, D. C."

From the above description taken in connection with the accompanying drawing, it is thought a clear and comprehensive understanding of the construction, operation and advantages of my invention may be had, and while I have shown and described the 45 device as embodying a specific structure, I desire that it be understood that such change may be made in said structure as do not depart from the spirit and scope of the invention as claimed. 50

Having fully described my invention, what I claim as new, and desire to secure by Letters Patent is:—

1. The combination with a needle plate of a shoe stitching machine, an upstanding 55 channeling knife thereon, of a guard plate correspondingly shaped to said needle plate positioned over the same in spaced superposed relation, and flanges on the edges of said guard plate adapted for frictional engagement with the sides of the needle plate 60 to hold said guard plate in position.

2. The combination with a needle plate of a shoe stitching machine having an elongated aperture therein, a channeling knife 65 disposed adjacent said aperture, of a guard plate adapted to be positioned over said needle plate, said guard plate having an alining aperture therein, and downwardly projecting flanges on the edges of said guard 70 plate adapted to hold the same in superposed spaced relation above the needle plate, whereby the channeling knife is rendered inoperative.

In testimony whereof, I affix my signature 75 hereto.

FRANK E. BROWN.
